Primary Examiner — Vy N Koenig

(74) Attorney, Agent, or Firm — Linda L Lewis;
CreatiVenture Law(57) **CLAIM**

The ornamental design for a ring box, as shown and described.

DESCRIPTION

FIG. 1 is a perspective view of a ring box showing our new design, in a closed configuration;

FIG. 2 is a top plan view thereof;

FIG. 3 is a left side view thereof, the right side being a mirror image thereof;

FIG. 4 is a bottom view of the ring box in a partially open configuration;

FIG. 5 is a front, top and left perspective view of the ring box in an open configuration;

FIG. 6 is a front and top perspective view thereof;

FIG. 7 is a top view of the insert portion of the ring box shown separately to show aspects of the design that may not be apparent in the other views;

FIG. 8 is a front view thereof;

FIG. 9 is a bottom view thereof; and,

FIG. 10 is a perspective view thereof.

1 Claim, 10 Drawing Sheets(56)
